UNITED STATES PATENT OFFICE.

JASPER E. SMISOR, OF MARION, INDIANA.

LOCK SWITCH.

Application filed March 27, 1925. Serial No. 18,733.

This invention relates to electric switches of that type controlled by a permutation lock, and particularly adapted for controlling the circuits of an automobile engine or 5 the like, altho applicable to other uses for which it is appropriate.

The object of the invention is to provide an improved device of this type, a characteristic feature of which is the positive operation of a switch lever by means of lock tumblers with which, when properly set, the lever will engage, and then when the tumblers are turned the contact carrying lever will close the circuit by movement in 10 one direction or open the circuit by movement in the other direction, the necessary pressure being applied thru or by the operating tumblers.

A further object of the invention is to 20 generally improve and simplify the construction of such lock switches.

The invention is illustrated in the accompanying drawings in which Fig. 1 is a vertical section on the line 1—1 of Fig. 2. Fig. 25 2 is a front elevation, partly broken away, showing the parts in one position. Fig. 3 is a similar view showing the parts in another position. Fig. 4 is a detail in perspective.

30 Referring specifically to the drawings, 6 indicates a casing conveniently set against an instrument board 7, the casing having a bushing or neck 8 which projects into a hole in the front board and forms a mounting for the lock parts which include a front plate 9 and a dial 10 fixed to a spindle 11 on which the tumblers 12 are mounted. The spindle extends thru the casing and receives a nut 13 at its rear end which confines a rear 35 lock plate 14 fitting in a recess in the removable rear plate 15 of the casing. The lock parts may be of any suitable or desired construction and operated in the usual manner to set the tumblers according to a predetermined combination.

45 Each tumbler has in its outer edge a notch 16, and when by manipulation of the tumblers these notches are set in line, the lock is set in position for operation of the switch.

50 The switch parts comprise a pair of blades 17 electrically connected to the wire 18 forming one side of the circuit, and a blade 19 electrically connected to the wire 20 forming the other side of the circuit, and adapted to enter between the blades 17 to close the

circuit. The blade 19 is carried by a piece of insulation 21 forming one arm of a bent lever, the other arm 22 of which projects from a hub 23 which is pivoted by a pin 60 24 to the casing, and when the lever is rocked, the switch will be opened or closed accordingly. The arm 22 is wide enough to extend across the edge of the tumblers, and the free end of the arm is formed on 65 one side with a rounded or cam surface 25, and on the opposite side with a recess or cavity 26, forming a point or edge 27 at the extremity of the arm, which is of proper size and shape to enter the tumbler notches 70 16 when they are lined up. The lever also carries a flat spring 28 adapted to strike the pin 29 projecting from the wall of the casing, and when the switch is opened, this spring is placed under tension sufficient to 75 engage the end 27 of the arm in the notches 16 when the tumblers are properly set.

The operation will now be understood: To 80 lock the switch in open position, as shown in Fig. 3, the knob is turned in a clockwise direction as viewed from the front, or as shown by the arrow in Fig. 3, and one or more of the tumblers will wipe over the cam surface 25 of the arm 22 and rock the lever from the position shown in Fig. 2 to 85 that shown in Fig. 3, thereby opening the switch. The action is positive, since the adjacent edge of the notch 16 will bear against said cam surface and force the lever over. To close the switch the tumblers must be 90 turned by manipulating the dial until the notches 16 are all in line with each other and with the end 27 of the arm 22. The spring 28, which is placed under slight tension by the locking operation, will then cause the end 95 27 to enter the notches slightly. Then by turning the knob and tumblers in counter clockwise direction, the opposite edge of the notches 16 will engage the end 27 and rock the lever by positive pressure, forcing the 100 blade 19 down between the blades 17 as shown in Fig. 2. This closes the switch, and it is held closed until the locking operation is repeated as above described. The cavity 105 26 gives the necessary clearance to enable the edge of the notches 16 to work around the edge 27 to the extent sufficient to avoid binding of the parts and insure complete closure of the switch.

The mounting of the lock includes a pair 110 of screws 30 which extend thru the front plate 9 and the instrument board and are

tapped into the casing, the heads of the screws being covered by the dial plate so that the lock cannot be tampered with from the front.

5 It will be obvious that until the notches 16 are registered with each other, and with the arm 22, the bearing of the free end of the arm against the rim or outer edge of the tumblers will hold the switch in open position, against any possibility of being closed. Furthermore the closure of the switch is 10 effected by pressure applied to the lever by means of the knob and the tumblers engaging the lever again after the latter enters the notches in the periphery of the tumblers.

15 I claim:

1. The combination with a switch lever, of a permutation lock having a set of rotary tumblers with notches in the edges thereof 20 in which the end of the lever may be engaged when the notches are registered therewith, said end of the lever having a cam surface at each side thereof engaged by either wall of the notches to positively swing 25 the lever in either direction by turning the tumblers.

2. The combination set forth in claim 1,

the lever being a bent lever having a contact at one end and having at the other end opposite cam surfaces against which either 30 wall of the notches will wipe to positively swing the lever when the tumblers are turned in either direction.

3. The combination stated in claim 1, the lever having a spring attached thereto and movable therewith, and a stop against which the spring strikes to place the same under tension when the lever is thrown to open position.

4. The combination with a knife switch 40 one member of which consists of a bent lever having a contact at one end and opposite cam surfaces at the other end, of a permutation lock having a set of rotary tumblers adapted to wipe over said cam surfaces 45 respectively to throw the lever to either open or closed position when the tumblers are turned in opposite ways, the tumblers having notches in the edges into which the end of the lever will engage when the notches 50 are registered therewith.

In testimony whereof, I affix my signature.

JASPER E. SMISOR.
